United States Patent Office

Des. 183,542
Patented Sept. 16, 1958

183,542

JUICE EXTRACTOR OR THE LIKE

Armand L. A. Posener, Los Angeles, Calif., and Austin E. Elmore, Mexico City, Mexico, assignors to Kitchen Master Appliances, Inc., Los Angeles, Calif., a corporation of California

Application November 25, 1957, Serial No. 48,625

Term of patent 14 years

(Cl. D89—1)

Fig. 1 is a front elevational view of a juice extractor or the like embodying our new design;

Fig. 2 is a side elevational view thereof;

Fig. 3 is a top plan view thereof.

We claim:

The ornamental design for a juice extractor or the like, substantially as shown.
